(57) **CLAIM**

The ornamental design for a panoramic camera mounting bracket, as shown and described.

DESCRIPTION

FIG. 1 is an isometric front top view of a panoramic camera mounting bracket showing our new design;

FIG. 2 is an isometric back bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a left side view thereof, showing movement of a mounting arm of the bracket from the upper left position shown in FIG. 5 to an intermediate position shown in FIG. 9; and,

FIG. 10 is a left side view thereof, showing movement of the mounting arm of the bracket from the upper left position shown in FIG. 5 to a lower right position shown in FIG. 10. The broken lines depict environmental subject matter and form no part of the claimed design.
